ADJUSTABLE MICROPHONE STAND

Robert F. Schuetz, Jackson Heights, N. Y., assignor to Radio Corporation of America, a corporation of Delaware

Application February 23, 1932, Serial No. 594,570

2 Claims. (Cl. 179—147)

This invention relates to a new and improved microphone stand and more particularly to stands of the type used in radio broadcasting.

An object of this invention is to simplify and improve microphone stands for radio broadcasting.

Another object of this invention is to provide a system of suspending the microphone and its associated amplifier in such manner that an artist's or speaker's vision past the microphone is not obscured, thus enabling him to more conveniently read his music or notes.

In radio broadcasting, when an artist plays his own accompaniment on a piano, he must be able to see conveniently the music or continuity sheets while playing. Similarly, when a speaker is seated at a table using notes for his speech, he should be able to look past the microphone to these notes.

Heretofore the microphone and amplifier were mounted on a base or upright standard which was massive and resulted in blocking the vision of the user in such a manner that the sheets of music or notes were generally placed to one side of the microphone. This position is awkward and not as desirable as one wherein the microphone is in the front center or directly above the artist's music or notes.

By means of the improved stand of my invention I am able to obtain this desired position. This invention utilizes the principle that when two weights are placed diametrically opposite each other, the weights will be balanced if a correct length is chosen for locating each particular weight upon an upright supporting post. For example, in the embodiment of this invention as will be seen from the drawing, the condenser microphone is placed at one end of a rather long radius arm. The associated amplifier, which is heavier, is placed at a comparatively short radius in diametrical opposition to it. Thus, suitable selection of these lengths permits the separation of microphone from the stand by any reasonable distance.

This invention consists of various features of construction as described and illustrated in the accompanying drawing. In the drawing, like reference characters refer to like parts throughout the several views, of which,

Fig. 1 is a perspective view of the improved stand;

Fig. 2 is an elevation of the amplifier with its associated leads;

Fig. 3 is a front elevation of the microphone with its associated adjustable elements, and

Fig. 4 is a side elevation of the microphone with its associated adjustable elements.

The general structure of this improved microphone stand is best shown in Fig. 1 wherein the standard or base member 1 supports an upright post 2 which is arranged to be adjustable in height by means of a shorter telescoping post 3. A set screw 4 is provided for clamping the telescoping post 3 when a desired height is obtained. This set screw 4 is threaded in the adjustable and rotating bushing 5, and although the height is fixed when clamped, the slot 19 allows for rotation of the arm. A T-shaped fitting 6 is fastened to the end of the telescoping upright post 3 and a short hollow tubular metallic member 7 is inserted in this fitting. At the other end of the member 7 there is fastened the microphone amplifier 8. A set screw 9 is provided to fasten the microphone amplifier to the member 7 or to alter the length between the T fitting 6 and microphone amplifier, should an adjustment of length to properly balance the microphone be required. The microphone 10 is adjustably mounted on fittings 11 and 18 which are retained in position by a rigid metallic tube 12 which is likewise inserted in the T fitting 6.

The metallic tube 12 is shown and described as rigid although it may in other modifications be of flexible metallic tubing.

Fig. 2 shows the microphone amplifier 8 mounted on the short tube 7. When the correct adjustment of the length between the T fitting 6 and the amplifier 8 is determined, it is secured by clamping the microphone 8 on the tube 7 by means of a set screw 9. Connection to the microphone is made by a single low capacity lead which is held in the exact center of the tubes 7 and 12 by successive layers of cotton braiding 14, or any other good insulating material. The metallic members 7 and 12 form the other conductor which is at ground potential.

Figs. 3 and 4 show in more detail the microphone 10 together with its associated adjustable fittings 11 and 18. The set screw 15 controls the rotatable adjustment of the microphone, the extent of rotation being controlled by a slot 17 in fitting 11, which allows for 180 degrees of rotation of the microphone 10. A fitting 18 is fastened to the end of the tube 12 and a pivot screw 19 joins the fittings 11 to 18 in a manner to rotate the microphone 10 through more than 90 degrees with the pivot screw 19 as a center. The microphone 10 is locked in its final position by the combined nut and handle 16.

In the operation of this improved adjustable

microphone stand the studio director determines the best position of the microphone, as regards light falling on the music, the artist's own taste, and the proper sound requirements, etc. Set

5 screws 15 and combined nut and handle 16 are then tightened. Then the proper connections are made to the transmitting apparatus by the cable 20 containing output and "B" battery leads 21. It will be noted that as the microphone arm is 10 mounted on a post which is rotatable through 180 degrees it can be placed on either the left or right hand side of the piano or table.

Although this invention has been described as embodied in a particular form and arrangement 15 of parts, it should be understood that it is capable of embodiment in other and different forms and not limited to those shown, except as such limitations are clearly imposed by the appended claims.

10 20 What I claim is:

1. An adjustable microphone and amplifier stand comprising a microphone and an amplifier, a base member, an adjustable upright tele-

scoping post and a hollow metallic supporting arm mounted on said post at a point where the microphone and amplifier are substantially balanced.

2. An adjustable microphone and amplifier stand for use in a broadcasting studio, comprising a base member, an adjustable upright supporting post, said post having inner and outer telescoping tubes, a bushing at the top of the outer tube retaining a set screw for clamping the inner tube when the desired height is obtained, a T-shaped fitting at the top of said inner tube, a long hollow arm secured to one side of the horizontal portion of said T fitting and a microphone secured to the other end of said arm, a short hollow arm secured to the other end of the horizontal portion of said T fitting, a microphone amplifier secured to the other end of said short arm, a single conductor located centrally within said long and short arms to electrically connect the microphone and amplifier together. 10 15 20
